UNITED STATES PATENT OFFICE.

EMILE DAVÈNES, OF SIERRA MADRE, CALIFORNIA.

BLOWER BRUSH.

Application filed October 13, 1926. Serial No. 141,303.

The object of the invention is to provide a device for the removal of dust which, when put in operation, will not only serve to loosen the dust from the surface being cleaned but will dispose of it by blowing it away from the operator as when such articles as screens are being cleaned.

With this object in view, the invention consists in a construction and combination 10 of parts of which a preferred embodiment is illustrated in the accompanying drawings, wherein:

Figure 1 is a side elevational view of the invention.

Figure 2 is a central vertical longitudinal sectional view.

Figure 3 is a transverse sectional view on the plane indicated by the line 3—3 of Figure 1.

20 The body portion of the brush is in the form of a housing or dust shield 10 with which there is connected the handle 11 so that the device as a whole may be readily grasped by the operator. The housing or shield 10 is open on the under face, as indicated at 12, and disposed within the opening is a rotary brush 14 carried on a spindle of which the journals are rotatably mounted in bearings carried by the bracket arms 25 15 mounted on opposite sides of the housing.

Within the housing is mounted a fan 16 having a shaft journaled in the end walls of the housing, one extremity of the shaft protruding beyond the housing for the reception of a pinion 17 which is in mesh with a

30 35 spur gear 18, the latter being mounted on

a stub shaft 19 carried by the end wall of the housing and being actuatable by means of a crank 20.

In the operation of the invention, which 40 is particularly adaptable for cleaning screens, the housing is placed against the screen with the rotary brush 14 in contact with the surface and the whole bodily moved across the screen, the brush loosening the dust and the fan 16 blowing the dust away from the operator when the fan is set in motion by the rotation of the spur gear 18 by means of its operating crank 20.

50 Lateral air intake openings 21 are provided in the end walls of the housing to provide for the drawing in of air which is discharged through the opening 12.

The invention having been described, what is claimed as new and useful is:

55 A device for the purpose indicated comprising a housing open on its under side and having a semi-cylindrical top side, a brush spanning and disposed within the area of the open side, a rotary fan within the housing directly above the brush and carried by a shaft rotatably mounted in said housing coincident with the axis of the top side, and a manual actuating crank operatively connected with the fan shaft, 60 the housing having lateral walls at the extremities of said top side and said walls having air intake openings adjacent said top side.

65 In testimony whereof he affixes his signature.

EMILE DAVÈNES.
